(57) CLAIM

I claim the ornamental design for a scrapbook paper and sticker organizer, as shown and described.

DESCRIPTION

FIG. 1 is a front perspective view of a scrapbook paper and sticker organizer showing my new design, the broken lines illustrating heat seals of the plastic material forming the invention;

FIG. 2 is a rear elevational view thereof;

FIG. 3 is a front elevational view thereof;

FIG. 4 is a top plan view thereof;

FIG. 5 is a bottom plan view thereof; and,

FIG. 6 is a right end elevational view thereof, the left end elevational view being the mirror image thereof.
